(74) Attorney, Agent, or Firm—Godfrey & Kahn, S.C.;
 William K. Baxter(57) **CLAIM**

The ornamental design for a lean magnetic soap holder, as shown and described.

DESCRIPTION

FIG. 1 is a perspective view of a lean magnetic soap holder showing the new design;

FIG. 2 is a right side elevational view thereof, the left side being a mirror image;

FIG. 3 is a front elevational view thereof;

FIG. 4 is a rear elevational view thereof;

FIG. 5 is a top plan view thereof; and,

FIG. 6 is a bottom plan view thereof.

A bar of soap is shown in broken lines for illustrative purposes only and forms no part of the claimed design.
